EUGENE GREGORY, OF YPSILANTI, MICHIGAN

ROTARY CHAIR CARRIER

Application filed August 8, 1927. Serial No. 211,404.

This invention relates to chairs and its object is to provide means whereby an ordinary chair may be readily converted into a rotatable and rocking or tilting chair. The invention provides an attachment or device which I term a rotary chair carrier upon which an ordinary chair may be mounted and secured—and when so mounted such chair can be readily turned while the occupant is seated therein so that he can face in any direction, and the chair can also be tilted or rocked upon the carrier if desired. With this novel attachment or device any ordinary chair may be readily converted into a rocking chair or rotatable and turnable chair without injuring its looks; and when thus converted it can be conveniently moved from place to place. Furthermore the rotary chair carrier upon which the chair is mounted will protect rugs, carpets and floors from injury by the legs or rockers of the chair.

In the accompanying drawings I have illustrated a rotary chair carrier embodying the invention and will describe the same with reference thereto and refer to the claims for summaries of the features for which protection is desired.

In said drawings:

Fig. 1 is a side view of the device partly broken away and showing a chair mounted thereon.

Fig. 2 is an enlarged sectional view on the line 2—2 Fig. 1 looking downward, and showing the rotary chair carrier in top plan.

Fig. 3 is an enlarged transverse section on the line 3—3 Fig. 2.

Fig. 4 is a bottom plan view of the rotary chair carrier, partly broken away.

Fig. 5 is an enlarged sectional view taken on line 5—5 Fig. 2.

Fig. 6 is a detail.

The rotary chair carrier, as shown, comprises a base member 1 which is preferably annular, and made of metal U-shaped in cross section, and preferably having an inwardly projecting flange 1^a on its upper inner edge. Mounted upon and over this base member 1 is a rotatable supporting member 2 which is also preferably annular and made of sheet metal and corresponds in diameter to the base mem-

ber 1, and is also preferably inverted U-shape in cross section. The base member 1 being open at top and the supporting member 2 being open at bottom.

The supporting member 2 is preferably rotatably supported upon the base member 1 by means of a series of spaced rollers 3 which are thin enough to freely engage in the hollow base and supporting members and be guided thereby and confined in position therein—and in turn prevent lateral displacement of the supporting member on the base member. These rollers 3 are of such diameter that the supporting member will be slightly raised above the base member as shown.

The rollers 3 may be kept in substantially uniform spaced relation by any suitable spacing means. Preferably I employ a metal ring 4 provided with radial struck-out lugs 4^a at spaced intervals. This ring is placed edge-wise in the channel of the base member and projects into the channel of the supporting member and the lugs 4^a project between adjacent rollers and permit slight relative play thereof—but prevent one roller overrunning another and keeps them approximately properly spaced.

While the supporting member 2 is free to rotate upon the base member 1 it should be held in proper relationship therewith so that it can not be lifted off when moving the carrier. Preferably metal fingers 2^a are attached to the inner side of the supporting member 2 and hooked under the flange 1^a of the base member 1 as shown—so that the members 1 and 2 are kept in proper relative position when the carrier is moved. Mounted upon the supporting member is a carrying member or frame which is preferably rectangular. The carrying member is preferably rectangular and formed of sheet metal and each side thereof has a horizontal flange portion 5 adapted to rest upon the top of the supporting member 2 and be fixedly attached thereto. At its outer edge part 5 has a depending flange 5^a which preferably extends almost to the bottom of the base but does not contact with the floor upon which the base rests. At its inner edge the portion 5 has an upstanding flange 5^b, at the top of which is an

inwardly projecting horizontal flange 5^c. This angular flanged construction makes a very rigid, strong and neat appearing carrier frame.

5 The member 5 is of such size that an ordinary chair can be stood thereon and have its legs fastened thereto by any suitable means so that the chair will be supported on the carrier.

10 Preferably I provide the supporting frame 5 with oscillatory rocker members 6 to which the chair legs may be attached. As shown upon two opposite sides of the carrying member 5 are mounted two tilttable or rocking members 6 which are preferably made of wood and are slightly longer than the sides of the carrying frame and project beyond the front and rear thereof as indicated in the drawings. These rocker members are preferably recessed on their inner surfaces as shown at 6^a so that at the outside of these shafts there is a portion 6^b which depends outside the outer flange 5^c of the frame 5. The top side of the recess is slightly curved 25 and is adapted to rest upon the flange 5 of the supporting member, the inner edge of the rocker member abutting closely against the flange 5^b of the supporting member. The members 6 are capable of slight rocking or 30 tilting movements and each is preferably yieldingly confined to the supporting member by means of a bolt or pin 6^a passing through a central slot 5^e in the side flanges 5^b of the supporting member and into the rocker member so as to hold the latter in position on the frame but permit the rocking member to tilt or rock longitudinally. The rocker members 35 6 are long enough to extend under and support the legs of an ordinary chair (or special 40 chair) (see Fig. 1) which may be placed upon the rockers and be secured thereto by means of screws 7 passed upwardly through the rockers and into the lower ends of the chair legs as shown.

45 When a chair is mounted upon this rotary chair carrier, as above described, the occupant of the chair can readily turn it to face in any direction; and when the chair is attached to the rocker members 6, as indicated 50 and described the chair can also be tilted or rocked. The attachment does away with the wear and tear on floors, rugs and carpets caused by ordinary chairs as the base member provides a large surface area for supporting the chair and the wear is on the attachment. The attachment is light and a chair mounted thereon can be moved from one place to another as readily as an ordinary chair.

To facilitate moving the chair from place 60 to place the supporting frame may be provided with diametrically opposite rollers or casters 8, which are normally pressed downward by springs 8^a, and which springs are so strong that when the chair is unoccupied the casters will tilt the base and chair up as indi-

cated in Fig. 6. This device enables the chair and rotary chair carrier to be readily moved without lifting it when unoccupied. When the chair is occupied the weight of the occupant overcomes the resistance of the springs 8 and the base will set flat upon the floor or surface upon which the chair rests; and said springs will not interfere with the turning or rocking movement of the chair when occupied.

I claim:

1. A chair carrier comprising a base member, a supporting member rotatably mounted upon the base member the base member and supporting member being annular and U-shaped in cross section; a carrying member mounted upon the supporting member, rocking members mounted on the carrying member and means for attaching a chair to said rocking members.

2. In a rotary chair support as set forth in claim 1, the carrying member formed of sheet metal and having horizontally disposed chair supporting portions with depending flanges at the outer edges of said portions and upstanding flanges at the inner edges of said portions.

3. A chair carrier comprising a base member and a supporting member having annular channels in their opposed faces; rollers in said channels mounting the supporting member upon the base member; a carrying member mounted upon the supporting member, formed of sheet metal having horizontally disposed chair supporting portions with depending flanges at the outer edges of said portions and upstanding flanges at the inner edges of said portions.

4. A rotary chair carrier, comprising a base member having an annular channel in its upper side, a supporting member having an annular channel in its lower side corresponding with the channel in the base member, rollers in said channels and mounting the supporting members upon the base member; a carrying member mounted upon the supporting member, rocker members mounted upon said carrying member, and means for attaching a chair to said rocker members.

5. In a rotary chair support as set forth in claim 4, the carrying member being formed of sheet metal having horizontally disposed chair supporting portions with depending flanges at the outer edges of said portions and upstanding flanges at the inner edges of said portions.

6. In a rotary chair carrier comprising a base member and a supporting member said members being annular and U-shaped in cross section, rollers mounting the supporting member upon the base member; means for spacing the rollers, a carrying member mounted upon the supporting member, and formed of sheet metal having horizontally disposed chair supporting portions with depending flanges at the outer edges of said

portions and upstanding flanges at the inner edges of said portions; and means for attaching a chair to said carrying member.

7. In a chair carrier as set forth in claim 6, the chair attaching means comprising rocker members mounted upon said carrying member and means for attaching a chair to said rocker member.

In testimony that I claim the foregoing as my own, I affix my signature.

EUGENE GREGORY.
